UNITED STATES PATENT OFFICE.

THOMAS JOSEPH STURTEVANT, OF WELLESLEY, MASSACHUSETTS, ASSIGNEE TO
STURTEVANT MILL COMPANY, A CORPORATION OF MAINE.

SCREENING OR SEPARATING MACHINE.

1,229,811.

Specification of Letters Patent. Patented June 12, 1917.

Application filed December 12, 1916. Serial No. 136,420.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Screening or Separating Machines, of which the following is a specification, reference being had therein to the accompanying drawings.

This invention relates to certain improvements in that class of inclined vibrating screening machines or separators in which the screens are percussively jarred when the 15 machines are in operation, as, for example, in the machines of the Sturtevant Patents Nos. 1,035,262 and 1,114,064. Machines of this kind are usually provided with upper, coarse or scalping screens and lower fine 20 mesh screens, which latter, to enable them to perform their operation most efficiently, are percussively jarred, as are also sometimes the former.

The present invention relates to certain 25 improved means for mounting and supporting the screen clothing and screens in the screen boxes or casings, as will hereinafter be fully set forth.

In the accompanying drawing Figure 1 30 is a cross section of a screen box or casing provided with screening members which are mounted therein in accordance with the present invention. Fig. 2 is a similar view showing a slightly different embodiment of 35 the invention from that shown in Fig. 1. Fig. 3 is a plan view illustrating the form of the invention shown in Fig. 1.

Referring to the drawing, 12 denotes a screen box or casing to the inner side walls 40 of which are permanently attached supports 13 which extend longitudinally of the casing, so as to run up and down, these supports 13 being preferably of sheet steel bent into angular form in cross section, as shown. 45 These supports 13 carry at the lower ends of their depending portions angle bars 14 which are preferably provided at their under sides with grooves 15. Suspended from the horizontal portions of the supports 13, by 50 bolts 16 are angle bars 17 to which are riveted vertical plates 18 provided at their lower ends with permanently attached angle bars 19 the horizontal portions of which are preferably provided with ribs 20 extending into 55 the grooves 15 of the angle bars 14.

The edges of the wire cloth for the fine mesh screen clothing 21 are clamped between the horizontal portions of the angle bars 14 and 19, so as to be removably mounted in place in the screen casing, this screen 60 clothing being thus conveniently secured in place so that it can be readily taken out when it becomes worn and when it is necessary that it should be replaced by new screen clothing. This clamping of the edges of 65 the screen clothing is effected by turning the nuts 22 on the bolts 16 so as to lift the plates 18 and angle bars 19, and thus bring the clamping jaws afforded by the horizontal portions of the angle bars 14 and 19 70 firmly together. Owing to the fact that this fine mesh screen clothing runs over the ribs 20 on the angle bars 19, and which ribs extend into the grooves 15 in the angle bars 14, the screen clothing will be effectively 75 gripped, by these parts so as to be held securely in place.

This fine mesh screen clothing 21 may be stretched, so as to be drawn properly taut, by turning the nuts 23 on the bolts 24 mounted in the casing 12 and passing through the depending portions of the angle bars 13 and which depending portions are sufficiently resilient so that they may be sprung outward toward the sides of the casing 12 to stretch 80 the screen clothing 21 and hold the same taut.

The wire mesh screen clothing is preferably provided, above and below, with protecting plates 25 riveted to said screen clothing; and superposed on said protecting plates are sockets 26 receiving the lower ends of the impact bars 27 on which hammers strike at intervals, as in the machines of the Sturtevant patents hereinbefore referred to, 90 for the purpose of vibrating the screen clothing. These protecting plates, in the form of the invention herein shown, are of less length than the width of the screen clothing 21, so that said screen clothing is free to be vibrated by the impact bars and their operating hammers.

To properly sustain the screen clothing 21 under the impact of the jarring operations, longitudinal supports 28, consisting preferably of steel rods or wires arranged beneath the sockets 26, are preferably provided; these rods or wires being sufficiently elastic, and being yieldingly supported on the screen casing by coil springs 37, to enable the jar-

ring operation to be properly effected, while serving to prevent such displacement of the screen clothing as would be liable to tear or injure it. The springs 37 are held in place 5 by nuts 38 on screw-threaded end portions of the rods 28.

The coarse or scalper screen 29, mounted in the screen casing above the fine wire mesh screen clothing 21, is, in the form of the invention herein shown, permanently attached 10 to a frame the sides of which consist of angle bars 30 resting on the horizontal parts of the angle-bar supports 13, this coarse wire mesh screen clothing being preferably clamped 15 between said angle bars 30 and elastic sheet-metal plates or strips 31 which bear against the sides of the inner walls of the screen casing 12 in such a manner as to prevent the material being screened from passing 20 over the side edges of the parts 30 and 31, at the sides of the scalper screen. Mounted on this coarse or scalper screen are guides 32 through which the impact bars 27 loosely pass, said impact bars being steadied near 25 their upper ends by guides 33 mounted on the cover 34 of the screen casing 12. From this it will be understood that the scalper screen 29, with its frame parts 30 and 31, may be removed from the screen casing 30 when the said cover of the screen casing is lifted.

In the form of the invention shown in Fig. 2 the constructions of all of the parts are the same as in Figs. 1 and 3, excepting 35 that the elastic supports for the fine wire mesh screen 21 are differently arranged. In this construction shown in Fig. 2 transverse supporting rods or wires 28^a are provided, these rods passing through brackets 35 ar- 40 ranged below the sockets 26 and attached, as are also said sockets, to said fine wire mesh screen clothing. These supporting rods 28^a, which, like the rods 28, are in the vertical planes of the impact bars 27, are preferably 45 of steel, extend loosely through bosses 36 attached to the sides of the screen casing 12, and each is encircled at one end by a coil spring 37^a arranged between the outer end of one of said bosses and a nut 38^a on a 50 screw-threaded end portion of the rod.

The rods 28, shown in cross section in Fig. 1, will preferably be mounted in the screen casing 12 in a manner similar to that shown for the mounting of the rods 28^a. 55 These rods 28^a are referred to in the plural for the reason that it will be understood that one of these rods will be provided for each of the transverse series of sockets 26, two or more transverse series of said sockets being 60 usually employed in machines of this kind, as will be understood by reference to the Sturtevant patents hereinbefore referred to.

It will be understood that the parts hereinbefore described which removably hold 65 the fine-mesh wire screen clothing 21, and by

which said screen clothing may be properly stretched, constitute built-in parts of the separator casing, so as to be permanent or non-removable elements, in contradistinction to a removable screen frame like that of the coarse or scalper screen member herein 70 shown and described.

As hereinbefore stated, the depending portions of the angle bars 13, which are preferably of sheet steel, are resilient, and the casing 12 is also preferably of more or less resilient sheet steel; so that the removably mounted fine wire mesh clothing is elastically supported at or near its edges, as well as by the resilient supporting rods 28 and 28^a beneath, and is thus so yieldingly mounted as to be free to vibrate readily for 80 efficient operation.

From the foregoing it will be understood that the invention provides convenient 85 means for removably mounting, as also for stretching and elastically supporting, the wire-mesh screen clothing of the fine screens of separating machines, and also provides convenient means for removably supporting 90 the coarse or scalper screens of separating machines.

The invention is not to be understood as being limited to the details of construction herein shown and described, as such details 95 may be varied widely, within the province of mechanical skill, without departing from the scope of the invention as defined in the appended claims.

Having thus described my invention I 100 claim and desire to secure by Letters Patent:

1. In a vibrating separator, the combination with a screen casing, of supports attached to said casing, clamping means sustained by said supports, and wire mesh 105 screen clothing removably held near its edges by said clamping means, said screen clothing being provided with protecting plates of lesser length than its width.

2. In a vibrating separator, the combination with a screen casing, of supports attached thereto, clamping means, sustained by said supports, for removably holding fine wire mesh screen clothing, and a coarse or scalper screen having at its edges frame 115 parts removably sustained by said supports.

3. In a vibrating separator, the combination with a screen casing, of supports attached thereto, clamping means, sustained by said supports, for removably holding fine 120 wire mesh screen clothing, means for stretching said screen clothing, and a coarse or scalper screen having at its edges frame parts removably sustained by said supports.

4. In a vibrating separator, the combination with a screen casing, of supports attached to the sides thereof and having depending resilient parts, lower clamping members sustained by said supports, wire mesh screen clothing having its edges ex- 125 130

tended between said clamping members, and means, sustained by said supports, for bodily adjusting said lower clamping members vertically for gripping and releasing the edges of said wire mesh screen clothing.

5. In a vibrating separator, the combination with a screen casing, of supports attached to the sides thereof and having depending resilient parts, upper clamping members attached to said depending parts, lower clamping members sustained by said supports, wire mesh screen clothing having its edges extended between said clamping members, and means, sustained by said supports, for bodily adjusting said lower clamping members vertically for gripping and releasing the edges of said wire mesh screen clothing, one of each pair of said clamping members being provided with a groove, and 20 the other of each pair of said clamping members being provided with a rib extending into said groove.

6. In a vibrating separator, the combination with a screen casing, of supports attached to the sides thereof and having depending resilient parts, upper clamping members attached to said depending parts, lower clamping members sustained by said supports, wire mesh screen clothing having its edges extended between said clamping members, means, sustained by said supports, for bodily adjusting said lower clamping members vertically for gripping and releasing the edges of said wire mesh screen clothing, 35 and bolts passing through said screen casing and provided with nuts for springing said depending resilient parts of said supports, for stretching said screen clothing.

7. In a vibrating separator, the combination with a screen casing, of supports attached to the sides thereof and having depending resilient parts, upper clamping members attached to said depending parts, lower clamping members sustained by said supports, wire mesh screen clothing having its edges extended between said clamping members, means, sustained by said supports, for bodily adjusting said lower clamping members vertically for gripping and releasing the edges of said wire mesh screen clothing, one of each pair of said clamping members being provided with a groove, and the other of each pair of said clamping members being provided with a rib extending into 50 said groove, and bolts passing through said screen casing and provided with nuts for springing said depending resilient parts of said supports, for stretching said screen clothing.

60 8. In a vibrating separator, the combination with a screen casing, of supports attached to the sides thereof and having depending resilient parts, upper clamping members attached to said depending parts, lower clamping members coöperating with

said upper clamping members, and vertically adjustable bolts having screw-threaded portions provided with nuts, and from which bolts said lower clamping members are supported, so that said lower 70 clamping members may be adjusted vertically bodily by turning said nuts, and wire-mesh screen clothing removably held by said clamping members.

9. In a vibrating separator, the combination with a screen casing, of supports attached to the sides thereof and having depending resilient parts, upper clamping members attached to said depending parts, lower clamping members coöperating with 80 said upper clamping members, vertically adjustable bolts having screw-threaded portions provided with nuts, plates supported from said bolts and lower clamping members attached to said plates, so that 85 said lower clamping members may be adjusted vertically bodily by turning said nuts, and wire-mesh screen clothing removably held by said clamping members.

10. In a vibrating separator, the combination with a screen casing, of supports attached to the sides thereof and having depending resilient parts, upper clamping members attached to said depending parts, lower clamping members coöperating with 90 said upper clamping members, vertically adjustable bolts having screw-threaded portions provided with nuts, and from which bolts said lower clamping members are supported, so that said lower clamping members may be adjusted vertically bodily by turning said nuts, wire-mesh screen clothing removably held by said clamping members, 100 and means for springing said resilient parts of said supports for stretching said screen clothing.

11. In a vibrating separator, the combination with a screen casing, of supports attached to the sides thereof and having depending resilient parts, upper clamping 110 members attached to said depending parts, lower clamping members coöperating with said upper clamping members, vertically adjustable bolts having screw-threaded portions provided with nuts, plates supported 115 from said bolts, lower clamping members attached to said plates, so that said lower clamping members may be adjusted vertically bodily by turning said nuts, wire-mesh screen clothing removably held by 120 said clamping members, and means for springing said resilient parts of said supports for stretching said screen clothing.

12. In a vibrating separator, the combination with a screen casing, of resilient supports attached to said casing, clamping means sustained by said supports, wire mesh stretched screen clothing held near its edges by said clamping means, impact devices for jarring said screen clothing, and 130

elastic rods extending beneath said impact devices and screen clothing, and yieldingly mounted in said casing, such yielding mountings serving to add to the resiliency of said rods and said stretched clothing.

13. In a vibrating separator, the combination with a screen casing, of supports attached to said casing, clamping means sustained by said supports, wire mesh screen

clothing removably held at its edges by said clamping means, impact devices for vibrating said wire mesh screen clothing, elastic rods yieldingly mounted in said casing and arranged beneath said screen clothing and in the vertical plane of said impact devices. 15

In testimony whereof I affix my signature.

THOMAS JOSEPH STURTEVANT.
